UNITED STATES PATENT OFFICE.

JOSEPH REES, OF NEW YORK, N. Y.

DESIGN FOR A TRAY.

SPECIFICATION forming part of Design No. 22,215, dated February 14, 1893.

Application filed December 29, 1892. Serial No. 456,707. Term of patent 3½ years.

To all whom it may concern:

Be it known that I, JOSEPH REES, a citizen of the United States, residing at New York, in the county and State of New York, have invented and produced a new and original Design for a Tray or Holder, of which the following is a specification, reference being had to the accompanying drawing, forming a part thereof.

10 This design has for its object to provide a novel and ornamental tray or holder for rings, lockets, and other articles of jewelry, and it consists in a tray having sides and a bottom wall which is provided with the representation 15 of an ornamental horse-shoe shaped figure.

The design is illustrated by the accompanying drawing in which the figure is a perspective view of the tray or holder.

In the drawing the letter A indicates the side walls of the tray or holder and B the bottom wall thereof, which is provided with the representation of an ornamental horse-shoe shaped figure D.

The design provides an ornamental tray which presents a characteristic and distinguishing appearance to the eye.

What I claim is—

The design for a tray or holder, substantially as shown and described.

In testimony whereof I have hereunto set 30 my hand in the presence of two subscribing witnesses.

JOSEPH REES.
